HENRI PERROT, OF PARIS, FRANCE, AND GERMAIN CALVIGNAC, OF MANNHEIM, GERMANY, ASSIGNORS, BY MESNE ASSIGNMENTS, TO BENDIX AVIATION CORPORATION, OF NEW YORK, N. Y., A CORPORATION OF DELAWARE

BRAKE SHOE

Application filed December 29, 1928. Serial No. 329,233.

This invention relates to brake shoes, and is illustrated as embodied in an arcuate rigid shoe for an internal expanding automobile brake. An object of the invention is to provide an inexpensive shoe of this character in which the lining can readily be renewed. The shoe has at least one and preferably two webs, which may be connected by a cam plate at one end of the shoe and which are arranged to be mounted on a pivot at the other end of the shoe. The friction part of the shoe may comprise a series of separate elements with pairs of lugs or equivalent portions secured to the shoe webs.

The above and other objects and features of the invention, including various novel and desirable details of construction, will be apparent from the following description of the illustrative embodiments shown in the accompanying drawing, in which:

Figure 1 is a side elevation of one form of shoe;

Figure 2 is a partial inside elevation, looking in the direction of the arrows 2-2 of Figure 1, and showing one of the friction elements;

Figure 3 is a section through the shoe on the line 3-3 of Figure 2;

Figure 4 is an end elevation, looking in the direction of the arrows 4-4 of Figure 2, and showing the cam plate;

Figure 5 is a perspective of a stamped steel cam plate;

Figure 6 is a partial side elevation showing a different form of friction element;

Figure 7 is an inside elevation, looking from the right in Figure 6;

Figure 8 is an inside elevation of a modified shoe having only one web; and

Figure 9 is a section through the modified shoe on the line 9-9 of Figure 8.

In the arrangement of Figures 1-4, the shoe comprises two stamped steel webs 10, formed with openings 12 for a pivot at their lower ends, washers 14 being welded to the sides of the webs about openings 12, if desired, to give a more extended bearing on the pivot. At their upper ends the webs are connected by means such as one or more transverse rivets 16, to lugs 18 projecting rear-

wardly between the webs from a novel stamped steel cam plate 20 having upper and lower flanges 22 embracing the ends of the webs between them.

The friction elements of this particular shoe are in the form of cast or molded blocks 24 of friction material such as cast iron, bronze, or phenolic condensation material, although they may be of other material faced with ordinary brake lining if preferred. 55 Each block has two end lugs 26 projecting between the webs 10 and formed with transverse openings for rivets 28 or other fastenings securing the block to the webs. In the arrangement of Figures 6 and 7 there is also 60 an intermediate lug or rib 30 for reinforcing the friction element.

In the arrangement of Figures 8 and 9, there is only one web 110, and the friction blocks 124 have pairs of lugs 126 embracing 70 the web between them and secured thereto by means such as transverse rivets 128.

While several illustrative embodiments of our invention have been described in detail, it is not our intention to limit the scope of the 75 invention to that particular embodiment, or otherwise than by the terms of the appended claims.

We claim:

1. A brake shoe having spaced webs, in 80 combination with a thrust plate of stamped steel having backwardly-projecting lugs engaging the sides and edges of the webs and secured to the sides of the webs.

2. A brake shoe having spaced webs, in 85 combination with a thrust plate having backwardly-projecting lugs secured to the respective webs, and having upper and lower flanges embracing the ends of the webs between them. 90

In testimony whereof, I have signed my name to this specification.

HENRI PERROT.

In testimony whereof, I have signed my 95 name to this specification.

GERMAIN CALVIGNAC.
